UNITED STATES PATENT OFFICE.

WILLIAM F. O'ROURKE, OF CHICAGO, ILLINOIS.

TRANSOM-LIFTER.

1,225,351.

Specification of Letters Patent.

Patented May 8, 1917.

Application filed August 17, 1916. Serial No. 115,358.

To all whom it may concern:

Be it known that I, WILLIAM F. O'ROURKE, a citizen of the United States, and a resident of Chicago, county of Cook, and State of Illinois, have invented certain new and useful Improvements in Transom-Lifters, of which the following is declared to be a full, clear, and exact description.

This invention relates to transom lifters, and its primary object is to provide a simple, efficient and practical device for adjusting transom windows or other hinged window sash. This invention relates in particular to transom lifters of that type which employ a stationarily supported rod adjacent the transom window, a rod clamp slidably mounted thereon and having rod gripping levers pivotally supported in the housing of the rod clamp, and an operating rod engaging said rod gripping levers and extending down to within reach of the operator. One of the objects of this invention is to provide a transom lifter of this type, capable of use either on the right or left hand side of a transom window. Another object is to provide a rod clamp in which the rod gripping levers are entirely concealed from view and wholly contained within the housing so as to be less likely of injury from external sources. With these and other objects and advantages in view, this invention consists in the several novel features herein-after fully set forth and claimed.

The invention is clearly illustrated in the drawing accompanying this specification, in which:—

Figure 1, is a front elevation of a simple form of my present invention applied to a door frame and transom window; Fig. 2, is a side elevation thereof, looking in the direction of the arrow 2 in Fig. 1; Fig. 3, is a central vertical section taken on the line 3—3 of Fig. 1; Fig. 4, is a horizontal section taken on the line 4—4 of Fig. 3, and Fig. 5, is a rear view of the rod clamp.

Referring to said drawing, the reference numeral 6, designates a door casing, to which is hinged a door 7, above which is the usual transom 8, having the transom window 9, hinged to it by hinges, one of which is seen at 10. Stationarily mounted upon said casing is a vertically extending rod 11, which as shown may be secured to the casing 6, by brackets 12, fastened upon the ends of the rod and screwed to the casing. Slidably mounted upon said station-

arily supported rod 11, is a rod clamp 13, which comprises a housing 14, preferably rectangular in shape and having a front wall 15, side walls 16, and end walls 17, the rear of the housing being open. The end walls 17, of said housing are formed with alined openings 18, for the reception of the stationarily supported rod 11, as is clearly indicated in Fig. 3.

Lugs 19, 19^a, are formed upon the inner face of the side walls 16, and are arranged in pairs as seen in Fig. 5, there being four pairs of lugs of which the lugs 19, are short ones, whereas the lugs 19^a, are long lugs. Between the opposing pairs of lugs are placed angularly disposed, rearwardly extending rod gripping levers 20, 21, each of which is formed with two holes near its free end, and the stationarily supported rod 11 passes through the two alined holes nearest the fulcrum; between said gripping levers is a coiled compression spring 22, which surrounds the rod 11, and bears against the rod gripping levers. Said levers are pivotally supported between the opposing pairs of lugs and may rock therebetween, the long lugs 19^a, serving to limit the movement of the rod gripping levers toward one another, and the oppositely disposed lugs 19, serving to limit the movement of said levers in the opposite direction. An operating rod 23, having a suitable handle or other grip 24, upon its lower end is slidably mounted in the lower rod supporting bracket 12, and extends through the outer alined holes in the rod gripping levers 20, 21, there being shoulders on said operating rod 23, adapted to engage with the outer sides of said levers.

For convenience, the rod is reduced in diameter, at the place where it passes through said levers, to form a shoulder 24^a, and the other shoulder is formed by a washer 25, which is secured upon the extreme end of the rod. The end walls 17, of the housing are notched out to receive the rod 23, as is clearly indicated in Figs. 3, and 4, whereby the levers may be wholly contained in the housing. The rod clamp housing is connected to the transom window 9, by a brace rod 26, and an angular transom bracket 27, and in order to make the transom lifter usable either on the right or left hand side of the transom window, I pivot the brace rod 26, to the middle of the front wall 15, of the rod clamp housing by providing two ears 28, on said front wall, which ears

are spaced apart to receive a fitting 28^a, that is secured upon the upper end of the brace rod. Said brace rod lies in the same plane as the stationarily supported rod 11, and operating rod 23, and is secured to the transom bracket 27, by a coupling 29, which is threaded upon the end of the brace rod 26, and is rotatively connected to the end of the angular transom bracket 27, whereby an adjustment is afforded to permit the angular transom bracket to be placed on either side of the brace rod. Said transom bracket 27, has the usual base 30, which is screwed to the transom window.

15 The operation of this device is readily apparent from the above description. Movement of the operating rod in either direction first swings the rod gripping lever (against which it pushes) until said lever 20 strikes an adjacent long lug 19^a, which limits its movement relative to the housing, and the continued movement of the operating rod 23, thereupon moves the clamp rod housing with it, thus moving the brace rod 26, 25 and transom bracket 27, and opening or closing the transom window, depending upon which direction the operating rod is moved.

It is to be observed that the rod gripping levers are wholly inclosed in the housing so 30 that they are not liable to become disarranged or interfered with from outside sources. Furthermore, by reason of the centrally located pivot connection between the brace rod and rod clamp housing and the 35 adjustable connection between the brace rod and transom bracket, the transom lifter is made usable on the right or left hand side of the transom window. Furthermore, by running the operating rod through the end holes 40 in the rearwardly extending gripping levers, the operating rod may lie close to the door casing.

More or less variation of the exact details of construction shown and described is possible without departing from the spirit of 45 this invention, and I desire, therefore, not to limit myself to the particular form of the invention shown and described, but intend in the following claims to point out all of 50 the invention disclosed herein.

I claim as new and desire to secure by Letters Patent:

Copies of this patent may be obtained for five cents each, by addressing the "Commissioner of Patents, Washington, D. C."

1. A transom lifter, comprising a stationarily supported rod, a rod clamp housing closed at the front and formed with spaced 55 lugs on its interior, said housing being slidably mounted thereon, angularly disposed, rearwardly extending rod gripping levers pivotally supported between said lugs in said housing, each having two holes in its 60 free end in alinement with corresponding holes in the other lever, and said rod passing through one pair of alined holes, a coiled compression spring encircling said rod and extending from one of said levers to the 65 other, an operating rod extending through the other alined holes of said levers and having shoulders engaging the outer sides of 70 said levers, a brace rod pivotally connected to a lug formed on the front wall of said 75 housing and lying in the same plane as the stationarily supported rod and operating rod, and an angular transom bracket adjustably secured to said brace rod and adapted to be secured to a transom window, at either 80 side of said rods.

2. A transom lifter, comprising a stationarily supported rod, a rod clamp housing slidably mounted thereon, said housing having a front wall, sides and ends and open at 85 the back, and having four pairs of spaced, rearwardly extending, oppositely disposed lugs cast upon the inner sides of the side walls, two angularly disposed, rearwardly extending rod gripping levers, each pivotally supported between two pairs of oppositely disposed lugs, and each lever having two holes in its free end in alinement with corresponding holes in the other lever, said 90 rod passing through two alined holes of said 95 levers, a spring extending between said levers, an operating rod extending through the other alined holes of the levers and having shoulders engaging the outer sides of said levers, a brace rod pivotally connected with ears extending out from the front wall of said housing, said brace rod lying in the same plane as the stationarily supported rod and operating rod, and an angular transom bracket adjustably secured to said brace rod 100 and adapted to be secured to a transom window at either side of said rods.

WILLIAM F. O'ROURKE.
